J. L. BENNETT

DEVICE OR IMPLEMENT FOR KILLING OR DISABLING INSECTS, FLIES, AND THE LIKE

Filed Feb. 9, 1923

UNITED STATES PATENT OFFICE.

JOHN L. BENNETT, OF DECATUR, ILLINOIS, ASSIGNOR TO U. S. MANUFACTURING CORPORATION, OF DECATUR, ILLINOIS, A CORPORATION OF ILLINOIS.

DEVICE OR IMPLEMENT FOR KILLING OR DISABLING INSECTS, FLIES, AND THE LIKE.

Application filed February 9, 1923. Serial No. 617,956.

To all whom it may concern:

Be it known that I, JOHN L. BENNETT, a citizen of the United States, a resident of Decatur, in the county of Macon and State 5 of Illinois, have invented a certain new and useful Device or Implement for Killing or Disabling Insects, Flies, and the like, of which the following is a specification.

This invention relates to improvements in 10 devices or implements for killing or disabling insects, flies, and the like and the principal object is to provide such a device which is very efficient for this purpose and exceedingly durable and effective in use.

15 A further object of this invention is the provision of a strong and resilient handle connected to a flexible and resilient body, the connection being very secure whereby the device as a whole has the necessary flexibility 20 and resiliency to obtain best results upon manipulation.

Further objects include the provision of 25 an advantageous form of advertising, a secure method of fastening and anchoring the handle within the body portion of the killer, and various other detailed improvements 30 which result in providing a device of maximum durability and efficiency.

To the accomplishment of the foregoing 35 and such other objects as may hereinafter appear, my invention consists in the construction, combination, and arrangement of parts hereinafter described and then sought to be defined in the appended claim, reference being had in the accompanying drawing 40 forming a part hereof and which shows merely for the purpose of illustrative disclosure a preferred embodiment of my invention, it being expressly understood, however, that various changes may be made in 45 practice within the scope of the claim without digressing from my inventive idea.

In the drawing,—

Figure 1 is a rear elevation of a device 45 constructed according to my invention, parts being broken away to facilitate the disclosure, and the long handle being broken for convenience.

Figure 2 is an elevational view of the 50 front of the striking or body part of the device.

Figure 3 is a cross section taken on line 3—3 of Figure 2 on an enlarged scale.

Referring now to the drawings, the numeral 1 designates the body of the device as

a whole, this being preferably formed of wire netting or other suitable reticulated material. It is to be noted that one edge is a selvage 2 and that both the side edges 3 and top edge 4 are folded upon themselves to 60 provide a reinforcement therearound. Flexible binding 5 is secured to both faces of the side and top edges of the device, this being preferably in the form of a single piece of soft material, such as felt and the like, 65 which is folded over the edges and secured thereto by stitching 6 which passes through the interstices of the body, thereby securely fastening the binding thereupon.

The body 1 is preferably rectangular in 70 shape and its lower corner portions 7 are folded upon the body along lines 8 so as to form portions of two ply thickness and provide a triangular extension beyond the transverse terminal portion of the binding 75 element. The top edges 9 of the folded portions extend in a horizontal direction and in substantial alinement with each other.

10 designates the handle member which is preferably formed of a suitable metallic 80 wire twisted upon itself as at 11 for substantially its entire length, the free ends being at the bottom. At the top said handle member is in the form of a triangular loop 12 having the sides 13 and the base 14. As 85 the triangle is inverted the base is at the top and it is connected to the sides by the rounded angles 15. The handle is provided with a suitable gripping member 16 preferably in the form of wood having the lower 90 end of the handle member suitably inserted in said gripping member and locked in position by means of the ferrule 17.

The handle member is secured to the body member by positioning said triangular loop 95 between the folded corner portions and the body, the sides 13 of said triangular loop closely fitting within the folds of said corner portions, for substantially their entire length, their angles of inclination being substantially the same. In order to hold these parts securely together I provide the securing means 18 which are passed through the folded corner portions and the body and are positioned just within the sides of said 100 triangular loop. These securing means 18 are in the form of elongated staples and are arranged to extend in parallel relation with the sides of said triangular loop, where- 105 by the handle member is securely wedged 110

in position and locked within the lower portion of the body member. Additional securing means 18' are passed through the body portion and the upper edges 9 of the folded portions, preferably passing through the flexible binding 5. These securing means 18' are also preferably elongated staples and are arranged parallel to the base 14 of said triangular loop. This 10 method of construction and manner of securing the parts together results in a very firm and secure fastening of the handle to the body so that the parts operate as a unit and give the resultant flexibility and 15 resilience of the part in manipulation.

For advertising purposes I may provide a card 20, this being substantially triangular in shape having its sides inclined on substantially the same angles as the lines 20-8 of the folds of the corner portions, so that said card fits tightly within the pocket formed between the folded corner portions and the body. This card is preferably positioned between the triangular loop 12 and 25 the body of the device and is fastened in position by the passage of securing means 18' therethrough. These securing means are clamped down tightly so that the parts

through which they pass are very firmly and securely held together. 30

What I claim is:

A device of the character described including in combination, a flexible body of substantially rectangular shape having its lower corner portions folded upon the body 35 along lines which converge toward a point and form a triangular extension, a handle member having diverging portions positioned between the body and said, folded portions at the said triangular extension 40 and fitting closely within the folds and securing means passing through the body and the folded portions and positioned between the diverging portions, additional securing means passing through the body and the 45 folded portions and located above the said diverging portions, and a binding element secured to the outer end and side edges of the body and having transverse terminal portions extending across the body at the 50 triangular extension and extending beyond the said folded portions.

In testimony that I claim the foregoing, I have hereunto set my hand this 30th day of January, 1923.

JOHN L. BENNETT.
